DOOR LATCH

Cecil R. Wolf, Rock Falls, and Neil M. Foulds, Sterling, Ill., assignors to Frantz Manufacturing Co., Sterling, Ill., a corporation of Illinois

Application June 12, 1940, Serial No. 340,144

9 Claims. (Cl. 292—169)

This invention relates to door latches for use on doors or closures of various kinds as, for example, those used on screen doors.

Generally stated, the object of the invention is to provide a novel and improved construction and arrangement whereby a reciprocating bolt is operated by a rotary handle, the axis of which latter reciprocates with the bolt.

It is also an object to provide certain novel details and features of construction that can be used in combination or which might be used separately in different combinations.

Another object is to provide a novel and improved construction whereby certain elements or features of construction, that were heretofore considered necessary, are entirely eliminated.

It is also an object to provide certain details and specific features of construction tending to reduce the cost of construction and to render a latch of this particular character more satisfactory in actual use.

To the foregoing and other useful ends, the invention consists in matters hereinafter set forth and claimed and shown in the accompanying drawings, in which—

Fig. 1 is a perspective of a door latch embodying the principles of the invention, showing the same mounted on the vertical edge portion of a door.

Fig. 2 is a vertical section, on a larger scale, taken in a vertical plane between the handle and the escutcheon, as shown in Fig. 1 of the drawings.

Fig. 3 is a similar view, but showing the parts in a different position.

Fig. 4 is a similar view, but showing the escutcheon in a vertical position and some of the parts removed or omitted for convenience of illustration.

Fig. 5 is a perspective view showing the different parts of the mechanism separated.

Fig. 6 is a horizontal section on line 6—6 in Fig. 1 of the drawings.

Fig. 7 is a view similar to Fig. 6, but showing the parts in a different position.

Fig. 8 is an enlarged vertical section on line 8—8 in Fig. 1 of the drawings.

Fig. 9 is a vertical section on line 9—9 in Fig. 6, looking in the direction indicated by the arrows.

Fig. 10 is a similar section on line 10—10 in Fig. 7 of the drawings.

Fig. 11 is a view similar to Fig. 10, but showing the parts in a different position and illustrating how the device is assembled on a door.

As thus illustrated, the invention comprises a

horizontal or reciprocating bolt 1, enclosed in a tubular casing 2, the door being bored horizontally between its inner and outer sides to receive said casing. A transverse retraction pin 3 extends through a horizontal transverse hole in the bolt and is provided with an enlarged middle portion 4 that is held in said hole. There is a coil spring 5 between the rear end of the bolt and the inner end of the casing, which pushes the bolt into locking position when the door is closed.

At each side of the door, there is an escutcheon 6, fastened in place by screws 7, or by any other suitable means. A hollow rivet on each end portion of the pin 3 rigidly connects the handle 8 with the cam plate 9, and a stationary cam plate 10 is held within the escutcheon. When the handle is turned about its horizontal and transverse axis, as shown in Fig. 3, one end portion of the plate 9 engages one end portion of the plate 10, and the bolt is retracted by the camming action between the plates 9 and 10 in the manner illustrated. The door can be unlatched by turning the handle in the opposite direction, as in that event the upper end of the plate 9 will then strike the upper end portion of the plate 10, and the action will be the same. Thus, the reciprocating latch bolt has a rotary handle, or preferably two handles, rotatable about an axis that moves back and forth with the bolt itself. It will be seen that the said handle 8 is rigid with the said rivet 11, and that the latter is then rigid with the plate 9, previously mentioned. In addition, it will be seen that the handle 8 is curved in such a manner that it starts first toward the adjacent vertical edge of the door, then curves around preferably in a short curve at 12, and then curves toward the door until it terminates in a short curve at its free or distal end 13, so that the handle is shaped to fit and conform to the hand, instead of compelling the latter to conform to the handle. Of course, in a sense, the hand must conform to the handle, but it will be seen that the shape of the latter is such that it is held in a very easy and natural grip of the hand. To permit movement of the pin 3 back and forth with the bolt, the sides of the tube 2 are provided with longitudinal slots 14 terminating in round enlargements 15. In addition, the escutcheon is provided with a horizontal slot 16 for the back-and-forth movement of said pin.

Preferably, an auxiliary locking device is provided, which comprises the plate 17 that has a projecting handle 18 extending through one edge of the escutcheon. This plate has an angular

slot 19 for the smaller diameter of the pin 3, and a spring plate 20 is provided with a bulge 21 for engaging said handle, to hold the latter either up or down. When the handle is down, as shown in Fig. 4, the latch bolt is free to reciprocate. But, when the handle 18 is up, then the lower angle portion of the slot 19 prevents horizontal movement of the pin 3, and the latch bolt is held in latched position. The plate 20 also has a horizontal slot 22, in which the pin 3 moves back and forth.

It will be seen that the round enlargements 15 of the two slots 14 only function when the latch bolt mechanism is being assembled on the door. For that purpose, the door is bored through its thickness at 23, transversely of the bore that is made for receiving the tubular casing 2 in which the latch bolt reciprocates. When the tube 2 is inserted, it is stopped in the position shown in Fig. 11, and the pin 3 can then be pushed through the holes 16 and also through the holes or enlargements 15, and through the transverse hole in the bolt, until the enlargement 4 at the middle of the pin is entirely within the latch bolt. Then the casing 2 can be fully inserted, and the escutcheons and handles can be put on, but in the reciprocation of the bolt, the enlargement 4 is never brought opposite the round holes or enlargements 15, hence there is no danger that the pin 3 will be accidentally pulled out endwise. In this connection, it will be seen that the oscillation of the plate 9, previously mentioned, is limited by reason of its engagement with the hollow escutcheon 6.

Thus, the axis of the rotary handle moves back and forth horizontally with the bolt, and the axis pin 3 can be arranged to engage something that will keep it from moving, when the door is latched, thus locking the door in latched condition. If it is desired to lock the door from either the inside or the outside, then each escutcheon may have a locking plate 17 inside thereof. But if it should be desired to only lock the door from the inside thereof, then only the inside escutcheon would have the said locking plate. Again, the rotary handle 8, through the medium of the cam plate 9, exerts a powerful leverage, when rotated in either direction, and hence a strong coil spring 5 can be employed, as the leverage is sufficient to easily overcome the yielding resistance of quite a heavy spring.

It is conceivable, of course, that other means could be used for engaging and moving the retractor pin 3, instead of the handle mechanism shown, and still insure the advantages of the shape and form of said pin 3 in the assembling of the latch mechanism on the door, without using a complicated housing made in two or more pieces, and without using a retractor pin that is reduced in its diameter at its middle, a strong pin being used instead, in combination with a simple one-piece tubular casing for the reciprocating latch bolt.

Thus the latch bolt mechanism shown and described is comparatively inexpensive to manufacture, being characterized by low cost production, and it is inexpensively installed by a carpenter on the door, in addition to being satisfactory to the user.

It is important to observe that the handle 8 is held against axial displacement on the pin 3 by the stationary plate 6 fastened to the door. This is because the plate 9 is fastened to the hollow rivet 11 and hence this plate 9, bearing against the inner surface of the plate 6, holds

the handle against outward axial displacement. In addition, it will be seen that the provision of the straight parallel guide edges of the slots 14 prevents endwise displacement of the pin 3 and thus obviates the necessity of circumferentially grooving the middle portion 4 of this pin for engagement with any retaining means. Moreover, with this construction, the handle 8 does not need to be fastened to the pin 3 and the latter is left free to rotate and the handle is free to rotate on the pin, thus obviating the necessity of providing any means for rigidly fastening the handle to the pin. The latch bolt is cylindrical and this is also true of the tubular sleeve 2, and they are both held against rotation by the pin 3, as the latter extends transversely through both the bolt and the said sleeve. This construction also obviates the necessity of cutting any slots in the door, which might be somewhat difficult, and instead the simple expedient of boring the round holes 23 is employed, so that the carpenter work necessary for installing the latch on the door is practically reduced to a minimum, for it is also only necessary to bore a round hole for the cylindrical sleeve 2 of the latch mechanism. It is also important to observe that the said sleeve 2 is a simple one-piece sheet metal affair and is not cast or made in two or more sections.

What we claim as our invention is:

- 30 1. A reciprocating latch bolt for a door latch, said bolt being bored transversely, a retractor pin extending through the transverse bore of the bolt, said pin being formed with an enlarged middle portion occupying said bore, a tubular casing for the bolt having lateral slots terminating at their rear ends in enlargements forming in effect round holes through which the said middle portion of the pin may pass in assembling the latch bolt mechanism on a door, together with a spring in the casing between the rear end of the latter and the rear end of the bolt, serving to force the latter into latching position when the door is closed.
- 35 2. A structure as specified in claim 1 having a handle mounted to rotate on a reduced end portion of said pin, and means rotatable with said handle and engageable with fixed abutment means for causing retraction of the bolt.
- 40 3. A reciprocating latch bolt assembly comprising a latch bolt, a casing receiving the bolt for longitudinal reciprocating movement therein, a retractor pin transversely received by the bolt and the casing, said casing having a longitudinally extending slot terminating adjacent its rear end in an enlarged opening, said pin having a circumferentially enlarged central portion receivable within the casing and adapted to pass through said enlarged opening but incapable of passing through said slot, said pin including extensions of relatively small transverse dimension operative to pass through the slot for retraction of the bolt when the transverse pin is operatively received by the bolt.
- 45 4. A reciprocating latch bolt assembly comprising a latch bolt, a casing receiving the bolt for longitudinal reciprocating movement therein, a retractor pin transversely received by the bolt and the casing, said casing having a longitudinally extending slot terminating adjacent its rear end in an enlarged opening, said pin having a circumferentially enlarged central portion receivable within the casing and adapted to pass through said enlarged opening but incapable of passing through said slot, said pin including extensions of relatively small transverse dimension

operative to pass through the slot for retraction of the bolt when the transverse pin is operatively received by the bolt, and spring means in said casing urging said bolt and retractor pin forwardly in the casing.

5. A reciprocating latch bolt assembly comprising a latch bolt, a casing receiving the bolt for longitudinal reciprocating movement therein, a retractor pin transversely received by the bolt and the casing, said casing having a longitudinally extending slot terminating adjacent its rear end in an enlarged opening, said pin having a circumferentially enlarged central portion receivable within the casing and adapted to pass through said enlarged opening but incapable of passing through said slot, said pin including extensions of relatively small transverse dimension operative to pass through the slot for retraction of the bolt when the transverse pin is operatively received by the bolt, spring means in said casing urging said bolt and retractor pin forwardly in the casing, and handle means journaled on said extensions for rotation about the axis of said pin, and means responsive to rotation of the handle for shifting said pin longitudinally of the slot to 25 retract the bolt.

6. In a latch bolt assembly for a door or the like, a longitudinally extending casing, a latch bolt mounted in said casing for movement longitudinally thereof, longitudinally extending slots formed on opposite sides of the casing, an actuator pin comprising a relatively large central portion transversely receivable within said casing and bolt, said relatively large portion being inoperative to pass through said slots, extensions of 30 relatively small lateral dimension projecting from said relatively large central portion and adapted to pass outwardly through said slots, at least one of said slots terminating adjacent its rear extremity in a relatively large aperture adapted to accommodate the said relatively large portion of the pin for insertion within the casing.

7. A latch bolt assembly for a door or the like comprising a latch bolt, casing means adapted to extend about the latch bolt for mounting the latch bolt for movement longitudinally thereof, pin means received transversely of the bolt and having portions extending outwardly of the casing for retracting the bolt, and means for actu-

ating said pin for moving the bolt to retracted position, said last named means comprising an actuating handle freely axially receivable upon said outwardly extending portions of the pin in 5 journalled relation for rotation on the pin and about the axis thereof and means operatively connected with the handle and operable by rotation of the handle about said pin for shifting the pin longitudinally of the casing.

10 8. A latch bolt assembly for a door or the like comprising a latch bolt, casing means adapted to extend about the latch bolt for mounting the latch bolt for movement longitudinally thereof, pin means received transversely of the bolt and having portions extending outwardly of the casing for retracting the bolt, and means for actuating said pin for moving the bolt to retracted position, said last named means comprising a unit freely axially receivable on said outwardly extending portions of the pin for rotation in journalled relationship on the pin and about the axis of said pin comprising a handle element, a shifting member operatively connected to said handle for rotation therewith, and means attachable to a door surface for retaining said handle operatively in rotative position upon said pin.

9. A latch bolt assembly for a door or the like comprising a latch bolt, casing means adapted to extend about the latch bolt for mounting the latch bolt for movement longitudinally thereof, pin means received transversely of the bolt and having portions extending outwardly of the casing for retracting the bolt, and means for actuating said pin for moving the bolt to retracted position, said last named means comprising a unit freely axially receivable on said outwardly extending portions of the pin for rotation in journalled relationship on the pin and about the axis of said pin comprising a handle element, a shifting member operatively connected to said handle for rotation therewith, and a housing embracing said shifting member and attachable to an outer door surface for holding said unit in axial position upon said pin, said housing including a reaction portion adapted to coact with said shifting member for urging the bolt and pin to be retracted position.
